UNITED STATES PATENT OFFICE

HARRY OSTROWER, OF BROOKLYN, NEW YORK

BUCKLE

Application filed November 22, 1929. Serial No. 409,084.

The subject-matter of the present invention relates to buckles and the improvements are directed to a novel and unique form of fastener whereby the free end of a belt, or 5 the like, is engaged with a loop arrangement directly forming a part of the buckle itself.

Those skilled in the art to which this invention appertains are aware that various forms of structures have been improvised 10 whereby one end of a belt may be attached to a buckle, the other end, or free end, of said belt, being engaged by the buckle and finally passed through a loop to maintain the same in a flat condition against a contiguous portion 15 of the belt. In the past it has been customary to form this loop of leather, of the like and suitably secured the same to a portion of the belt.

In the invention about to be disclosed in detail, it is proposed to provide a loop, for the purpose aforesaid, said loop becoming substantially a part of the buckle and the clamping means whereby the belt-strap is secured in position. Hence, my improved buckle will 25 comprise the buckle proper, the clamping means, also carrying said buckle, and finally a loop arrangement; all combining to form a unitary structure which requires but the addition of the leather belt for subsequent offering to the public as a finished article.

Another object of the invention resides in the provision of a buckle of the above-mentioned character which embodies a loop arrangement, either formed separately, or integral 35 with certain clamping means and which may be made of metal or any other suitable material.

As will presently appear, the arrangement is exceedingly simple, neat in appearance and in view of easy assemblage may be offered to the public at a low price, thus assuring its commercial success.

With these objects in view, together with others which will appear as the description proceeds, the invention resides in the novel formation, combination and arrangement of parts, all as will be described more fully hereinafter, illustrated in the drawings, and particularly pointed out in the claims.

In said drawings:

Figure 1 is a front elevation of my improved buckle, having associated therewith the usual belt strap, the latter having one end clamped to said buckle and with its free end engaged with the latter in the usual manner 55 and finally having its extremity passed beneath a loop arrangement forming a part of said buckle.

Fig. 2 is a sectional view taken longitudinally of the parts shown in Fig. 1 to depict 60 clamping means and the loop arrangement imprisoning the end of the belt strap.

Fig. 3 is a view like unto Fig. 1, but with the free end of the belt strap removed.

Fig. 4 is an edge view of the parts shown 65 in Fig. 3.

Fig. 5 is an inverted plan view of the buckle removed from the belt strap.

Fig. 6 is a transverse sectional view, slightly enlarged, and taken on the line 6—6 of 70 Fig. 3.

Referring now more in detail to the accompanying drawings, wherein like characters of reference denote similar parts throughout the several views, let 10 indicate a typical form of belt strap having its free end 11 provided with apertures 12 for the reception of the tongue or prong portion 13 of the buckle 14. Said buckle 14 is preferably formed from a single piece of material, 80 suitably decorated, and having its rear portion rounded as indicated at 15, (see Fig. 5) for pivotal engagement with the loop extensions 16 formed in the plate 17. It will be noted in Fig. 3 that said extensions 16 are 85 spaced to permit the attachment of the prong 13 to said rear portion 15, said prong 13 being bent to form an eye 18 for this purpose.

As clearly shown in Figs. 2 and 5, the sides of said plate 17 are bent laterally to 90 provide flanges 19 and 20, each being apertured, as indicated at 21 and 22 for the reception of pintles 23 extending from the clamping jaw 24, the latter being angular in cross-section, one leg being provided with serrations 95 25, while the other leg 26 serves as means for operating said jaw. The rear portions of said flanges 19 and 20 are cutaway, as indicated at 27, and this cut is continued into the adjacent portion of said plate 17 to 100

permit the insertion of the loop arrangement 28, and in order that the latter may be maintained in this position the rear marginal portion of said plate 17 is slightly deflected, as indicated at 29, (see Fig. 4). As shown in 5 Fig. 6, said loop 28 may be formed from a single piece of material, bent as shown, but obviously a continuous loop may be provided.

From the foregoing it is apparent that my 10 invention comprises but a few simple parts, which are grouped or combined to form a unitary structure embodying a buckle, a plate 15 pivotally carrying said buckle, said plate further being constructed in a manner to permit the attachment of a clamping jaw and finally a loop arrangement for the reception of the free end of a belt strap clamped at its other end by said clamping jaw.

The article will be sold to the public as a 20 unitary structure and hence it is only necessary to affix one end of the belt strap beneath said plate and operate the clamping jaw, whereupon the strap is affixed as indicated in Fig. 2. After the free end has been passed 25 through the buckle and adjusted within the proper aperture 12, the extremity of said strap is inserted within the loop arrangement 28, as shown in Fig. 2. The buckle is adapted to withstand hard usage and permits 30 the interchanging of belt straps as desired.

Various slight changes might be made in 35 the general form and arrangement of the parts described without departing from the invention, and hence I do not limit myself to the precise details set forth, but consider myself at liberty to make such changes and alterations as fairly fall within the spirit and scope of the appended claims.

I claim:

40 1. In a buckle, a plate pivotally supporting a buckle, apertured flanges depending from the sides of said plate, a clamping jaw mounted in said apertured flanges and adapted to be operated to affix one end of a belt strap beneath said plate, said flanges presenting cutaway portions, and a loop insertible 45 within said cutaway portions and affixed to said plate, said loop being adapted to receive the free end of a belt strap.

50 2. In a buckle, a plate pivotally supporting a buckle, a clamping jaw cooperating with said plate and adapted to be operated to affix one end of a belt strap beneath said plate, said plate presenting cutaway portions adjacent 55 the rear thereof and a loop insertible within said cutaway portions and adapted to be secured by deflecting the rear marginal portion of said plate, said loop being adapted to receive the free end of a belt strap.

60 In testimony whereof I affix my signature.
HARRY OSTROWER.
